US00D948044S

(12) **United States Design Patent** (10) **Patent No.:** **US D948,044 S**
(45) **Date of Patent:** **** Apr. 5, 2022**

(54) **FLUID TRANSFER DEVICE**

(71) Applicant: **ICU Medical, Inc.**, San Clemente, CA (US)

(72) Inventor: **Thomas E. Fangrow**, Mission Viejo, CA (US)

(73) Assignee: **ICU Medical, Inc.**, San Clemente, CA (US)

(**) Term: **15 Years**

(21) Appl. No.: **29/674,367**

(22) Filed: **Dec. 20, 2018**

Related U.S. Application Data

(60) Division of application No. 29/586,575, filed on Dec. 5, 2016, now Pat. No. Des. 837,983, which is a continuation of application No. PCT/US2016/064467, filed on Dec. 1, 2016.

(51) **LOC (13) Cl.** **24-02**

(57) **CLAIM**

The ornamental design for a fluid transfer device, as shown and described.

DESCRIPTION

FIG. 1 is a front perspective view of a fluid transfer device; FIG. 2 is a rear perspective view of the device of FIG. 1; FIG. 3 is a front view of the device of FIG. 1; FIG. 4 is a back view of the device of FIG. 1; FIG. 5 is a right side view of the device of FIG. 1; FIG. 6 is a left side view of the device of FIG. 1; FIG. 7 is a top view of the device of FIG. 1; and, FIG. 8 is a bottom view of the device of FIG. 1. The broken lines shown in FIGS. 1-9 illustrate portions of the fluid transfer device that form no part of the claimed design.

1 Claim, 7 Drawing Sheets
